UNITED STATES PATENT OFFICE.

EDWIN LE ROY ANTONY, OF CAMERON, TEXAS.

WRENCH.

SPECIFICATION forming part of Letters Patent No. 596,235, dated December 28, 1897.

Application filed June 28, 1897. Serial No. 642,601. (No model.)

To all whom it may concern:

Be it known that I, EDWIN LE ROY ANTONY, a citizen of the United States, and a resident of Cameron, in the county of Milam, State of Texas, have invented a certain new and useful improvement in the means used in adjusting the clamping-jaws of wrenches to nuts or taps to be screwed on or off their bolts or holdings; and I do hereby declare the following to be a full, clear, and exact description of the invention, such as will enable others skilled in the art to which it appertains to make and use the same, reference being had to the accompanying drawings, making a part of this specification, and to the letters of reference marked thereon, and in which similar letters of reference indicate corresponding parts.

My invention relates to improvements in monkey-wrenches; and its object is to provide an improved construction of the same whereby the clamping-jaws may be quickly and readily adjusted to the nut or tap which is to be engaged thereby.

The invention consists in the novel construction and combination of parts herein-after described and claimed.

In the accompanying drawings, Figure 1 is a side elevation of a wrench constructed in accordance with my invention. Fig. 2 is a side elevation of the handle or frame. Fig. 3 is a similar view of the movable jaw and its shank. Fig. 4 is a vertical section on the line $z z$, Fig. 1. Fig. 5 is a similar section on the line $x x$. Fig. 6 is a detail view of the ratchet-catch. Fig. 7 is a detail view of the sleeve-blank before being bent into form. Fig. 8 is an end view of the sleeve. Fig. 9 is a detail view of the handle or frame, looking from the under side and showing the holes in which the pins of the catch work.

In the said drawings the reference-letter F designates a frame or handle made of metal and comprising the arms $n n$, connected together at one end, and one of said arms at the opposite end being formed with a stationary jaw k . Said arm is also formed with an enlargement y at the opposite end. There is a space between said arms to receive a movable shank T, cut away at the inner end, forming a reduced portion T', having upon one edge a number of rack-teeth y^2 and at the outer end formed with a head H and a

jaw k' , movable with the shank. The object of the enlargement y is to form a contracted space to receive the reduced end T' of the shank T.

The letter J designates a sleeve consisting of a metal plate bent over near the center, forming two parallel portions $a a$, which embrace the arms $n n$. This sleeve is formed with holes h , through which and also through holes h' in one of the arms n pass bolts or rivets r , by which the sleeve is firmly secured to the handle or frame. At one end said sleeve is formed with lugs o , with which engage lugs e on a catch or rack-plate C, formed with teeth t , adapted to engage with the teeth on the shank T. This plate is located in a recess b in one of the arms n and is provided with pins p , passing through holes m in the arm. Coiled springs S are interposed between said catch and the arm to throw the former into engagement with the teeth of the shank. The purpose of the lugs e and o is to prevent the rack-plate C from being forced out of its seat by the coiled springs S should the shank T be entirely withdrawn from the handle, the lugs e in such case engaging with or abutting against the lugs o .

In use the coiled springs will force the catch or rack-plate into engagement with the teeth of the shank of the movable jaw, thus holding the latter in place. To adjust the movable jaw, the said catch or rack-plate is pushed away from the shank, so as to disengage its teeth therefrom, when the shank can be moved out in a rapid manner. The catch is then released, when the coiled springs will again force the catch or rack-plate into engagement with the shank and, sliding easily over each other inwardly, the adjustment is quickly made to a nut or bolt by pressing the head H and the handle toward each other, holding over the nut or bolt, thus clasping it between jaws $k k'$ by the engagement of the teeth of the catch or rack-plate with the shank-teeth automatically.

Having now fully described my invention, what I claim as new, and desire to secure by Letters Patent, is—

1. In a wrench, the combination with the frame or handle comprising the connected arms, one of which is formed with a jaw, a recess and an enlarged portion, and the sleeve

embracing said arms and secured to one of the same and formed with lugs at the inner end, of the movable shank having a jaw at the outer end and the other end reduced and formed with rack-teeth, the movable catch or rack-plate provided with lugs adapted to engage with the lugs of the sleeve, and the coiled springs, substantially as described.

2. In a wrench, the combination with the frame or handle comprising the connected arms, one of which is formed with a jaw, a recess and an enlarged portion, and the sleeve

consisting of the bent plate embracing said handle and secured thereto and provided with lugs at the inner end, of the movable shank having a jaw at one end and reduced at the other end and formed with rack-teeth, the movable rack-plate or catch provided with lugs, the guide-pins and the coiled springs, substantially as described. 15

EDWIN LE ROY ANTONY.
